UNITED STATES PATENT OFFICE.

ANDREW F. HOWE, OF GRANITE CITY, ILLINOIS, ASSIGNOR TO COMMONWEALTH STEEL COMPANY, OF ST. LOUIS, MISSOURI, A CORPORATION OF NEW JERSEY.

SAND-MILL.

1,218,403.

Specification of Letters Patent.

Patented Mar. 6, 1917.

Application filed February 7, 1916. Serial No. 76,724.

To all whom it may concern:

Be it known that I, ANDREW F. HOWE, a citizen of the United States, residing at Granite City, in the county of Madison and 5 State of Illinois, have invented a new and useful Improvement in Sand-Mills, of which the following is a specification.

My invention relates to a sand mill, which ordinarily consists of a circular-shaped pan 10 on which are rollers, and having an upper circumferential rim or flange, the pan being partly filled with sand to be mixed, which on the revolution of the pan passes beneath and is crushed and kneaded by the rollers, 15 thereby necessitating, when the batch is finished, the removal of the sand from the pan by shovels.

My invention has for its object to dispense with the said rim or flange and provide 20 means for automatically effecting an uninterrupted passage of the sand beneath the mixing rollers and delivery therefrom, and from the pan when desired, into a waiting receptacle or on to a conveyer without the 25 use of shovels or other hand-operated tools.

It consists in features of novelty as hereinafter described and claimed, reference being had to the accompanying drawing forming part of this specification, whereon, 30 Figure 1, is a top plan of my improved sand mill, and Fig. 2, an end elevation thereof.

Like letters and numerals of reference denote like parts in both figures.

35 My improved sand mill comprises a horizontally arranged circular-shaped table *a* which is the equivalent of the ordinary pan used in this class of mill, without the circumferential rim or flange thereof.

40 The table *a* is fixed centrally to an upright shaft *b* which passes therethrough and is journaled at its lower end below the table *a* in a step-block or bearing *c* secured to the foundation of the machine, the upper 45 portion of the shaft *b* above the table *a* passing through a preferably, bushed bearing *d* fixed to the top cross beam *e* of the framework of the machine.

To the upper end of the vertical shaft *b* 50 above the cross beam *e* is fixed a bevel toothed wheel 1 (shown by dotted lines in Fig. 2) which is engaged by a bevel toothed pinion 2 fixed on a horizontal shaft 3 (broken away) which is mounted in bearings 4, 4', carried by the top cross beam *e*

and adapted to be rotated by belt and pulley or otherwise as found most suitable.

On the table *a* are mounted preferably, two, circular rollers *f* which normally bear circumferentially on the table *a* and are arranged side by side opposite to each other, one on each side of the vertical shaft *b* at a suitable distance therefrom respectively.

Centrally through the rollers *f* passes freely an axle *g* which is non-revoluble but 65 movable with the rollers *f* in a vertical plane obedient to the action of the latter in their operation on the sand as hereinafter particularly referred to; each end portion of the axle *g* being inclosed in a vertically 70 elongated box-shaped pocket 5 which projects from the inside face of the corresponding side piece *h* of the framework of the machine, and on the axle *g* there is an adjustably fixed collar 6 which bears against 75 the face of the pocket 5 and so prevents longitudinal movement of the axle *g*; similarly, each roller *f* is held in position on the axle *g* by two collars 6' which are adjustably fixed on the axle *g* and bear respectively, against the corresponding side of the roller *f*. Furthermore, through the axle *g* in the middle is formed a vertical and longitudinally elongated opening 7 which surrounds and permits free rotation of the 80 vertical shaft *b* without obstruction by the axle *g* when the latter is displaced vertically in the operation of the machine.

Connecting the two opposite side pieces *h* of the framework together below the top 90 cross beam *e* and at a suitable distance from the table *a*, are two horizontal cross braces or beams *i*, one on each side of the vertical shaft *b*, and from each brace *i* at right angles thereto and at each side thereof, to wit, outwardly toward the edge of the table *a* and inwardly toward the vertical shaft *b*, projects a horizontal arm *j* having a vertical slotway 8 therethrough which extends practically the entire length of the two arms *j* 100 and through the brace *i*.

Spanning the single slotway 8 thus formed is a series of preferably, rectangular-shaped washer plates 9, 10, arranged in pairs, the plates 9, 10, of each pair being 105 opposite to each other, above and below the slotway 8 respectively, as shown, the said pairs of the series being at suitable intervals along the arms *j*, and through each pair of washer plates 9, 10, passes vertically 110

2

a screw-threaded rod 11 having upper and lower nuts 12, 13, which are adapted to tighten and hold the washer plates 9, 10, to the arms *j*.

5 To the bottom end of each rod 11 is pivotally mounted a preferably, concave circular revoluble disk *k* which is arranged in a preferably, vertical plane, and approximately in contact with the upper surface of 10 the table *a*, the disk *k*, by means of the nuts 12, 13, being adjustable to any desired inclination to a radius of the table, and distant from the latter. Also, projecting outward from each brace *i* adjacent and parallel to the corresponding arm *j* and in the same plane therewith, is an arm *j'*, the arm *j'* of one brace *i* being to the right, and that of the other brace *i*, to the left of the vertical shaft *b* as seen in Fig. 1, each arm *j'* 15 having a slotway 8', upper and lower washer plates 9', 10', screw-threaded rod 11', nuts 12', 13', and concave circular revoluble disks *k'*, all the said parts being similar to the corresponding parts of the arms *j* above described, except that on the rod 11' above the upper nut 12' is fulcrumed a hand lever 14 which extends therefrom outward beyond the edge of the table *a* within reach of the operator, the lever 14 being provided with a 20 suitable locking device 14' and connected by a turnbuckle 15 (omitted in Fig. 2 to avoid confusion) to a second lever 16 which is fulcrumed to a rod 17 passing vertically downward through a boss or bearing 18 which is 25 formed on the outer closed end of the outer arm *j*, and to the lower portion of the rod 17 below the boss 18 is hinged a vertically arranged gate or deflecting plate 19, so that, on moving the hand lever 14 in a direction 30 opposite to the rotation of the table the disk *k'* and gate 19 can be closed together, or separated from each other to form a space between them as desired.

In operation, assuming the disks *k* and *k'* 35 to be in their several positions respectively, as seen particularly in Fig. 1, with the gate or deflecting plate 19 at the upper side of the vertical shaft *b* closed against and aligned with the corresponding disk *k'*, and with 40 the gate or deflecting plate 19 at the lower side of the shaft *b* opened outward and separated from the corresponding disk *k'* so as to leave a space *x* between them, rotation being imparted to the table *a* in the direction of the arrows *y*, and consequently by 45 the table *a*, to the rollers *f* in the direction

of the arrows *z*, the sand to be mixed being fed through a pipe 20 (indicated by dotted lines) or in any other suitable manner, and with the sand, water through an auxiliary pipe (not shown) or otherwise, is deposited on the table *a*, preferably, at the middle thereof adjacent to the right hand roller *f* and being revolved with the table *a* will thereby be carried in a practically circular path, and owing to centrifugal force, gradually directed outward toward the edge of the table *a*, and in so doing passes between the table *a* and one of the rollers *f* by which it is crushed and kneaded, passing therefrom between the disks *k* and *k'* and by these guided and directed between the table *a* and the other roller *f* by which it is further mixed and kneaded and passes therefrom partly, between the disks *k* to be again 75 passed beneath the rollers *f* and partly eventually between the outermost disks *k*, *k'*, and the gate or deflecting plate 19 toward the outer edge of the table *a* from which it is delivered by centrifugal force on to a conveyor 21 (indicated by dotted lines in Fig. 1) or into any other suitable receptacle.

By having both the gates or deflecting plates 19 in the open position as seen in Fig. 1 at the lower side of the vertical shaft *b* the sand may be retained on the table *a* for any desired length of time as found necessary for the more thorough mixing and kneading thereof; also by varying the inclination of the disks *k* and *k'* the sand may be repeatedly passed a more or less number of times between the table *a* and rollers *f* before being discharged from the table *a*.

I claim:

In a sand mill, the combination of a circular table pivotally supported and revoluble in a horizontal plane, a roller axially revoluble in a vertical plane and adapted to bear circumferentially on the table at right angles to a radius thereof, a pivotally mounted 95 circular disk revoluble in a practically vertical plane at an inclination to a radius of the table, and approximately in contact circumferentially with the latter, means for varying the said inclination, a deflecting 100 plate adapted to coöperate with the said disk, and means for rotating the table.

ANDREW F. HOWE.
